UNITED STATES PATENT OFFICE.

JOHN H. MCGEHEE AND MARCUS T. BROWER, OF SAN JOSE, CALIFORNIA.

CARTON.

SPECIFICATION forming part of Letters Patent No. 728,404, dated May 19, 1903.

Application filed July 1, 1902. Serial No. 113,992. (No model.)

To all whom it may concern:

Be it known that we, JOHN H. MCGEHEE and MARCUS T. BROWER, citizens of the United States, residing at San Jose, in the county of 5 Santa Clara and State of California, have invented certain new and useful Improvements in Cartons; and we do hereby declare the following to be a full, clear, and exact description of the same.

10 This invention relates to a carton for fruit, candy, and the like. In this class of devices it is desirable that the package shall not only serve as a convenient carrier, but also that it shall serve the purpose of presenting an attractive and enticing display of the contained articles. It is also desirable that the package shall be cheap and simple of construction and be readily adaptable to the methods of packing or filling usually employed.

15 The object, therefore, of the present invention is to provide a carton cheap and simple in character which will serve not only as a carrier for the transportation of ripe fruit and the like, but shall also serve to display its 20 contents in an attractive manner. These objects are accomplished by means of the devices illustrated in the accompanying drawings, in which—

Figure 1 is a plan view of our carton as a 25 carrier, showing its contents arranged therein. Fig. 2 is a plan view, on a smaller scale, of the carton or sheet from which the carrier shown in Fig. 1 is formed.

Referring to the drawings, 1 is a carton, 30 box, receptacle, or carrier of any suitable form adapted to be opened from its lower side and having its top provided with a display-opening 2, occupying less than the area enclosed by the sides. This opening 2 is cut 35 from the material of the top, leaving a flange or edge 3 surrounding it and projecting inwardly from the lateral sides of the box or carrier, an inwardly-projecting flange to the sides of the box forming a passe-partout of 40 the top of the box or carrier and integral therewith.

The opening 2 may be of any suitable or 45 ornamental character, and its inner edge may be formed into an ornamental design to add 50 attractiveness to the packing.

Referring to Fig. 2, it will be seen that the carton from which the carrier is formed has its central portion or that part of the carton which when formed into a carrier constitutes the top provided with a proportionately large 55 central opening from which the material has been removed. The carton is suitably formed, slit, notched, creased, and perforated, so that when properly bent and interlocked it will form the display box or carrier illustrated in 60 Fig. 1. The part 3 within the central square of dotted lines constitute the top of the box or inwardly-projecting flange of the sides. The parts marked 4 form the sides of the box when bent along the dotted lines where they 65 adjoin part 3. By means of their notches 5 they interlock with each other. The parts 6 and 7 bent along their dotted lines constitute an outer or double side to the box over the locked sides and also a closing and locking 70 portion for the bottom of the carrier. The hook-formed part 8 interlocks with the slit 9 to secure the bottom against accidental opening. The parts 10 and 11 constitute protecting-strips forming a partial double bottom for 75 the box. The openings 12 and 13 are ventilating-openings.

Having now described our invention, what we claim as new, and desire to secure by Letters Patent, is—

80 A flat box-blank having a part adapted to constitute the top of the box provided with a display-opening of less area than the part to leave a continuous surrounding flange, parts secured to the edges of the top part arranged 85 to constitute the box sides and ends, and parts provided with means arranged to interlock at a point beneath the top part to form the bottom of the box; substantially as described, whereby said blank when folded will 90 form a box closed at all points save the opening in the top; substantially as described.

JOHN H. MCGEHEE.
MARCUS T. BROWER.
